UNITED STATES PATENT OFFICE.

HOWARD M. LEONARD, OF JACKSON, MICHIGAN.

TRACTOR.

1,293,815.

Specification of Letters Patent. Patented Feb. 11, 1919.

Application filed January 31, 1918. Serial No. 214,612.

To all whom it may concern:

Be it known that I, HOWARD M. LEONARD, a citizen of the United States, residing at Jackson, county of Jackson, State of Michigan, have invented certain new and useful Improvements in Tractors, of which the following is a specification.

This invention relates to improvements in tractors.

10 My present improvements relate particularly to the four wheel drive type of tractors illustrated in my application for Letters Patent filed Feb. 2, 1917, Ser. No. 146,118.

The main objects of my invention are:

15 First, to provide an improved driving mechanism for the steering wheels.

Second, to provide an improved driving mechanism for the steering wheels, which are so disposed as to constitute, in effect, a 20 single centrally disposed traction wheel.

Third, to provide an improved driving mechanism for tractors which is effectively incased or inclosed.

25 Further objects, and objects relating to structural details, will definitely appear from the detailed description to follow.

I accomplish the objects of my invention by the devices and means described in the following specification. The invention is 30 clearly defined and pointed out in the claims.

A structure which is a preferred embodiment of my invention is clearly illustrated in the accompanying drawing, forming a part of this specification, in which:

25 Figure I is a plan view of the rear portion of my improved tractor with certain details and parts omitted.

Fig. 1^A is a plan view of the front portion thereof with certain details and parts 40 omitted entirely or partially broken away.

Fig. II is a detail side elevation of the rear portion of my improved tractor shown in Fig. I.

45 Fig. II^A is a detail side elevation of the front portion of my improved tractor shown in Fig. II.

Fig. III is a detail view partially in vertical section on a line corresponding to line 3—3 of Fig. I^A, Fig. II^A, and Fig. IV.

50 Fig. IV is a detail view partially in vertical longitudinal section on a line corresponding to line 4—4 of Fig. III.

Fig. V is a detail view partially in section on a line corresponding to line 5—5 of Fig. III.

55

Fig. VI is a detail section on a line corresponding to line 6—6 of Fig. III.

In the drawing similar reference characters refer to similar parts throughout the several views, and the sectional views are 60 taken looking in the direction of the little arrows at the ends of the section lines.

Referring to the drawing, I provide a running gear frame comprising side members 1 connected by cross bars 2. At the 65 front end the frame is provided with a cross member 3 constituting a support for the front traction wheels 4, as will be herein-after described.

The rear traction wheels 5 are mounted 70 on the axle 6. The mounting of the axle and driving connections for the traction wheels being made the subject matter of an application filed concurrently herewith, Ser. No. 214,613, are not described in detail 75 herein.

The axle 7 of the front traction wheels 4 is carried by the yoke-like standard 8 having a vertical spindle 9 arranged in bearing 10 carried by the cross member 3.

80 A bushing 11 is provided for the bearing 10.

A roller thrust bearing 12 is provided at the lower end of the bearing 10 or between it and the standard 8. A steering gear 13 is secured to the standard in the structure illustrated, the gear being formed to receive the thrust bearing 12.

85 A pinion 14 is mounted on the shaft 15 to mesh with the gear 13. On the upper end 90 of this shaft 15 is a gear 16 with which the worm 17 on the steering shaft 18 meshes. This steering shaft 18 is provided with a steering wheel 19 at its rear end in position to be operated by the operator occupying 95 the seat 20. The gears 16 and 17 are inclosed by a gear box 21.

The spindle of the wheel standard is hollow to receive a spindle shaft 22. The cap plate 10' of the bearing 10 is provided with 100 a bearing for the shaft 22. The upper end of the shaft 22 is further supported by a bearing designated generally by the numeral 23 carried by the gear box 24. The lower

end of the shaft 22 is supported by the shafting bearing 25 at the lower end of the standard spindle.

At its upper end the shaft 22 is provided with a beveled gear 26 meshing with a gear 27 on the propeller shaft 28. At its lower end the spindle shaft is provided with a beveled gear 29 meshing with the beveled driving gear 30 of a differential driving means, designated generally by the numeral 31. This differential driving means is inclosed in a housing or gear box 32, which is connected with the box of the bearing 25. The differential shafts 33 are provided with pinions 34 which mesh with the internal gears 35 secured to the traction wheel hubs 42. The outer hub members 4' are keyed to the inner or main hub members 42 by keys 4''. The caps 50 are secured to the hubs by the screws 51, a packing 52 being provided to prevent the escape of lubricant around the axle. The outer ends of these differential shafts are supported by bearings 36 carried by the housing members 37 supported by the axle 7. These plates have brackets 38 carrying bearings 39 disposed on the inner sides of the pinions 34. The housing members 37 have peripheral flanges 40. On these flanges are closure plates 41 having central openings to receive the hubs 42 of the traction wheels, the plates 41 being provided with packings 43 about the hubs.

With the parts thus arranged the bearing and driving parts are entirely inclosed and protected, which is a feature of very great advantage in tractors and like structures used for plowing, harrowing, and like work.

The motor 44 is conventionally shown, as is also the driving clutch 45 thereof. The motor 44 and transmission 46 are mounted upon a frame 47, which is in turn mounted upon the main frame. As the mounting of this frame 47 forms no part of my present invention, it is not further described herein.

The driving shaft 48 is provided with suitable universal joints as are also the front propeller shaft 28 and the rear propeller shaft 49. The yoke-like wheel standard 8 is channel shaped in cross section. The steering gear 13 rests thereon and is provided with a rib fitting into the channel, thereby providing a very strong connection for the gear to the standard.

I preferably employ the transmission shown in my copending application, filed Oct. 15, 1917, Ser. No. 196,643, and as the details thereof form no part of my present invention they are not illustrated or described herein.

With the parts arranged as I have illustrated and described, I provide a structure in which the wheel spindle is very effectively supported to withstand the heavy strains to which it is subjected.

I have not attempted in the accompany-

ing drawing to maintain the relative proportion of the parts, and various parts are shown conventionally. Neither have I attempted to illustrate or describe certain modifications or embodiments which I contemplate, as I believe the disclosure made will enable those skilled in the art to which my invention relates to embody or adapt the same as may be desirable under varying conditions.

Having thus described my invention, what I claim as new and desire to secure by Letters Patent, is:

1. In a tractor, the combination of a running gear frame, a yoke-like standard provided with a hollow spindle, a bearing for said spindle carried by said frame, an axle carried by said standard, traction wheels mounted in close relation upon said axle between the arms of the standard, a spindle shaft disposed longitudinally of said spindle to project between said traction wheels and provided with a gear at its upper end, a cap plate for said spindle bearing provided with a bearing for said spindle shaft below said gear thereon, a propeller shaft having a gear meshing with said gear on said spindle shaft, a gear box inclosing the upper end of said spindle shaft and said gears and provided with a bearing for the upper end of said shaft, a shafting box for the lower end of said shaft mounted at the lower end of said spindle, a differential means comprising differential shafts disposed between said traction wheels and having differential driving connection with said spindle shaft, a gear box for said differential means provided with bearings for said differential shafts and connected to said shafting box, gears on said traction wheels, pinions on said differential shafts meshing with said gears on said traction wheels, housing members mounted on said axle to embrace said traction wheel gears and pinions provided with bearings for said differential shafts, said housing members having annular shoulders thereon, collars mounted on said differential gear box to embrace the said shoulders of said housing members, and closure plates for the outer ends of said housing members embracing the hubs of the traction wheels.

2. In a tractor, the combination of a running gear frame, a yoke-like standard provided with a hollow spindle, a bearing for said spindle carried by said frame, an axle carried by said standard, traction wheels mounted in close relation upon said axle between the arms of the standard, a spindle shaft disposed longitudinally of said spindle to project between said traction wheels, a shafting box for the lower end of said shaft mounted at the lower end of said spindle, a differential means comprising differential shafts disposed between said traction wheels

- and having differential driving connection with said spindle shaft, a gear box for said differential means provided with bearings for said differential shafts and connected 5 to said shafting box, gears on said traction wheels, pinions on said differential shafts meshing with said gears on said traction wheels, housing members mounted on said axle to embrace said traction wheel gears 10 and pinions provided with bearings for said differential shafts, said housing members having annular shoulders thereon, collars mounted on said differential gear box to embrace the said shoulders of said housing members, and closure plates for the outer ends of said housing members embracing the hubs of the traction wheels.
3. In a tractor, the combination of a running gear frame, a yoke-like standard provided with a hollow spindle, a bearing for said spindle carried by said frame, an axle carried by said standard, traction wheels mounted in close relation upon said axle between the arms of the standard, a spindle 25 shaft disposed longitudinally of said spindle to project between said traction wheels, a shafting box for the lower end of said shaft mounted at the lower end of the spindle, a differential means comprising differential 30 shafts disposed between said traction wheels and having differential driving connection with said spindle shaft, a gear box for said differential means provided with bearings for said differential shafts and connected to 35 said shafting box, gears on said traction wheels, pinions on said differential shafts meshing with said gears on said traction wheels, and housing members mounted on said axle to embrace said traction wheel gears and pinions provided with bearings for said differential shafts disposed at each 40 side of said pinions thereon.
6. In a tractor, the combination of a running gear frame, a yoke-like standard provided with a hollow spindle, a bearing for said spindle carried by said frame, an axle carried by said standard, traction wheels mounted in close relation upon said axle between the arms of the standard, a spindle 45 shaft disposed longitudinally of said spindle to project between said traction wheels, a shafting box for the lower end of said shaft mounted at the lower end of said spindle, a differential means comprising differential 50 shafts disposed between said traction wheels and having differential driving connection with said spindle shaft, a gear box for said differential means provided with bearings for said differential shafts and connected to 55 said shafting box, gears on said traction wheels, pinions on said differential shafts meshing with said gears on said traction wheels, and housing members mounted on said axle to embrace said traction wheel gears and pinions provided with bearings for said differential shafts.
4. In a tractor, the combination of a running gear frame, a yoke-like standard provided with a hollow spindle, a bearing for said spindle carried by said frame, an axle carried by said standard, traction wheels 60 mounted in close relation upon said axle between the arms of the standard, a spindle shaft disposed longitudinally of said spindle to project between said traction wheels, a shafting box for the lower end of said spindle mounted at the lower end of said spindle, a differential means comprising differential 65 shafts disposed between said traction wheels and having differential driving connection with said spindle shaft; a gear box for said differential means provided with 70
- bearings for said differential shafts and connected to said shafting box, gears on said traction wheels, pinions on said differential shafts meshing with said gears on said traction wheels, and housing members mounted on said axle to embrace said traction wheel gears and pinions provided with bearings for said differential shafts.
5. In a tractor, the combination of a running gear frame, a yoke-like standard provided with a hollow spindle, a bearing for said spindle carried by said frame, an axle carried by said standard, traction wheels mounted in close relation upon said axle between the arms of the standard, a spindle 75 shaft disposed longitudinally of said spindle to project between said traction wheels, a shafting box for the lower end of said shaft mounted at the lower end of the spindle, a differential means comprising differential 80 shafts disposed between said traction wheels and having differential driving connection with said spindle shaft, a gear box for said differential means provided with bearings for said differential shafts and connected to 85 said shafting box, gears on said traction wheels, pinions on said differential shafts meshing with said gears on said traction wheels, and housing members mounted on said axle to embrace said traction wheel gears and pinions provided with bearings for said differential shafts disposed at each 90 side of said pinions thereon.
6. In a tractor, the combination of a running gear frame, a yoke-like standard provided with a hollow spindle, a bearing for said spindle carried by said frame, an axle carried by said standard, traction wheels mounted in close relation upon said axle between the arms of the standard, a spindle 95 shaft disposed longitudinally of said spindle to project between said traction wheels, a shafting box for the lower end of said shaft mounted at the lower end of the spindle, a differential means comprising differential 100 shafts disposed between said traction wheels and having differential driving connection with said spindle shaft, a gear box for said differential means provided with bearings for said differential shafts and connected to 105 said shafting box, gears on said traction wheels, pinions on said differential shafts meshing with said gears on said traction wheels, and housing members mounted on said axle to embrace said traction wheel gears and pinions provided with bearings for said differential shafts disposed at each 110 side of said pinions thereon.
7. In a tractor, the combination of a running gear frame, a yoke-like standard provided with a hollow spindle, a bearing for said spindle carried by said frame, an axle carried by said standard, traction wheels mounted upon said axle between the arms of the standard, a spindle shaft disposed longitudinally of said spindle to project between 115
- 120
- 125
- 130

said traction wheels and provided with a gear at its upper end, a propeller shaft having a gear meshing with said gear on said spindle shaft, a differential means comprising differential shafts disposed between said traction wheels and having differential driving connection with said spindle shaft, a gear box for said differential means provided with bearings for said differential shafts, gears on said traction wheels, pinions on said differential shafts meshing with said gears on said traction wheels, housing members mounted on said axle to embrace said traction wheel gears and pinions provided with bearings for said differential shafts, disposed at each side of said pinions thereon, and steering means comprising a gear secured to said standard spindle.

8. In a tractor, the combination of a running gear frame, a yoke-like standard provided with a hollow spindle, a bearing for said spindle carried by said frame, an axle carried by said standard, traction wheels mounted upon said axle between the arms 20 of the standard, a spindle shaft disposed longitudinally of said spindle to project between said traction wheels and provided with a gear at its upper end, a propeller shaft having a gear meshing with said gear 25 on said spindle shaft, a differential means comprising differential shafts disposed between said traction wheels and having differential driving connection with said spindle shaft, gears on said traction wheels, 30 pinions on said differential shafts meshing with said gears on said traction wheels, housing members mounted on said axle to embrace said traction wheel gears and pinions provided with bearings for said differential shafts, and steering means comprising a gear secured to said standard spindle.

9. In a tractor, the combination of a running gear frame, a standard provided with a hollow spindle, a bearing for said spindle 45 carried by said frame, an axle carried by said standard, traction wheels mounted upon said axle, a spindle shaft disposed longitudinally of said spindle to project between said traction wheels, a differential means 50 comprising differential shafts disposed between said traction wheels and having differential driving connection with said spindle shaft, a gear box for said differential means, gears on said traction wheels, pinions on said differential shafts meshing with said gears on said traction wheels, housing members mounted on said axle to embrace said traction wheel gears and pinions, said housing members having annular shoulders 55 thereon, collars mounted on said differential gear box to embrace the said shoulders of said housing members, and closure plates for the outer ends of said housing members embracing the hubs of the traction wheels.

65 10. In a tractor, the combination of a run-

ning gear frame, a standard provided with a hollow spindle, a bearing for said spindle carried by said frame, an axle carried by said standard, traction wheels mounted upon said axle, a spindle shaft disposed longitudinally of said spindle to project between said traction wheels, a differential means comprising differential shafts disposed between said traction wheels and having differential driving connection with said spindle shaft, a gear box for said differential means, gears on said traction wheels, pinions on said differential shafts meshing with said gears on said traction wheels, housing members mounted on said axle to embrace said traction wheel gears and pinions, and closure plates for the outer ends of said housing members embracing the hubs of the traction wheels.

11. In a tractor, the combination of a running gear frame, a standard provided with a hollow spindle, a bearing for said spindle carried by said frame, an axle carried by said standard, traction wheels mounted upon said axle, a spindle shaft disposed longitudinally of said spindle to project between said traction wheels, a differential means comprising differential shafts disposed between said traction wheels and having differential driving connection with said spindle shaft, a gear box for said differential means, gears on said traction wheels, pinions on said differential shafts meshing with said gears on said traction wheels, housing members mounted on said axle to embrace said traction wheel gears and pinions, said housing members having annular shoulders thereon, and collars mounted on said differential gear box to embrace the said shoulders of said housing members.

12. In a tractor, the combination of a running gear frame, a standard provided with a hollow spindle, a bearing for said spindle carried by said frame, an axle carried by said standard, traction wheels mounted upon said axle, a spindle shaft disposed longitudinally of said spindle to project between said traction wheels, a differential means comprising differential shafts disposed between said traction wheels and having differential driving connection with said spindle shaft, a gear box for said differential means, gears on said traction wheels, pinions on said differential shafts meshing with said gears on said traction wheels, and housing members mounted on said axle to embrace said traction wheel gears and pinions.

13. In a tractor, the combination of a yoke-like standard provided with a spindle, an axle supported by the arms of said standard, traction wheels mounted upon said axle between the arms of said yoke, a spindle shaft disposed through said spindle to
